UNITED STATES PATENT OFFICE.

ROBERT K. FLOETER, OF CHATHAM, ONTARIO, CANADA.

FANNING-MILL.

SPECIFICATION forming part of Letters Patent No. 429,565, dated June 3, 1890.

Application filed July 21, 1888. Serial No. 280,591. (No model.) Patented in Canada March 1, 1888, No. 28,586.

To all whom it may concern:

Be it known that I, ROBERT K. FLOETER, of Chatham, in the county of Kent, Province of Ontario, Canada, have invented a new and useful Improvement in Fanning-Mills, (for which I have obtained a patent in Canada dated March 1, 1888, No. 28,586,) of which the following is a specification.

The object of my invention is to provide a novel mechanism for separating grain from impurities as the former is descending from a feed-hopper to an upper riddle; and to this end my invention consists in the combination of devices hereinafter described and claimed, reference being made to the accompanying drawings, in which—

Figure 1 is a longitudinal sectional view of a fanning-mill embodying my invention. Fig. 2 is a side elevation of same. Fig. 3 is an enlarged detail plan view of the connections for shaking the upper shoe. Fig. 4 is an end view of the lower shoe. Fig. 5 is a perspective view of the lower shoe, showing the crank-shaft through which said shoe is operated.

S and S' designate shoes suspended at two sides of the machine on spring-hangers H and H', respectively.

C designates a connecting-rod, which connects the underside of the shoe S with the crank on the crank-shaft A. This connecting-rod C is pivotally secured to the crank on the crank-shaft A, and is hinged to the shoe S at the other end. Motion is communicated to this shoe S by the chain belt B from the chain-wheel D, rigidly secured on the shaft E, to the chain-wheel D', rigidly secured on the crank-shaft A, and motion is communicated from the driving chain-wheel D' to the shaft E by a chain belt B', passing over said wheel D' and another chain-wheel rigidly secured on the shaft E on the opposite side of the machine to that shown in Fig. 2.

On the shaft E the fans F F are rigidly secured, so that as the shaft E is operated the fans F F are also operated to raise a large current of air, which is conducted by the deflecting-board I in the direction shown by arrows $\alpha\alpha$ on the grain above the riddle R before it falls on the latter. The action of this current or blast of air on the grain as it falls from the hopper K is to separate therefrom

and blow out at the end of the machine all the chaff, dust, and other light impurities. The thistle-heads and other heavier impurities that are too heavy to be blown free from the machine are blown as far as the smut-board J, which conducts them off at the end of the machine. This separates this class of impurities from the grain before it falls on the riddle R, so that the grain is perfectly free to pass through said riddle, which it does, and falls on the screens L and L' in the shoe S.

The riddle R and smut-board J are adjustable or movable in the shoe S', but may be rigidly secured therein when required.

C' is a connecting-rod, which connects one arm m' of an elbow-lever M with the chain and crank wheel D, and the end of this connecting-rod C' is attached to the wheel D at any required distance from the center, so that as the chain-wheel D is operated the elbow-lever M is also operated. The other arm m^2 of this elbow-lever M is pivotally connected to the upper shoe S' by a connecting-rod C², so that as this machine is operated the shoe S' is shaken laterally, as well as the riddle R and smut-board J, secured therein, which agitates the grain on the riddle R and assists the grain in passing through said riddle.

The deflecting board or valve I is pivoted at its lower edge in the shoe S' below the inner end of the riddle R. The deflecting-board is rearwardly inclined and extends slightly above the upper surface of the riddle, and it is adapted to be adjusted or moved on its pivot in order to deflect the blast of air from the fans F to any required point. As shown in accompanying drawings, it is in the proper position for most kinds of grain to separate the impurities from the grain before they fall on the riddle R; but if it is required to separate oats from wheat it is preferable to adjust the deflecting-board to the position shown by dotted line in Fig. 1—that is, to a position beneath the inner end of the riddle. This is accomplished by first moving the adjustable or movable riddle R sufficiently to allow the deflecting-board I to be adjusted to the desired position.

N designates a cylindrical fan-chamber, in which the fans F F work, the air to which chamber passes through the opening O, and the quantity is governed to a certain extent

by a pivotal valve N' , which covers about one-half of the opening O , as shown in Fig. 2; but in Fig. 1 this valve is thrown back, leaving the opening perfectly free.

5 P is the bottom board of the shoe S, which conducts the screenings into the drawer or receptacle P' .

T is a rack, in which the screens L L' may be held at any required inclination.

10 U U are connecting-pins, which form a communication between the screens L L' to communicate the vertical vibrations from the screen L' to the screen L .

V is a valve adjusted by a crank-screw W 15 to retain the grain in the hopper K or permit it to flow into the mill in any desired quantity.

X is a roller secured by and revolving perfectly free in bearings X' , which are rigidly 20 secured to the frame of the machine, and one of these rollers is secured at each side of the shoe S, as shown in Fig. 4.

25 X^2 X^3 are serrated plates rigidly secured opposite the rollers X to a board X^3 , which is hinged to the frame of the shoe S, so that as the shoe S is operated lengthwise of the machine by the crank-shaft A and connecting-rod C and connections the serrated plate passing over the roller X gives the board X^3 a 30 vertical movement, as well as the screens L L' , by which the grain is delivered perfectly free, even when the screens are at a very slight incline. This board X^3 , being hinged to the shoe S, may be thrown back, as well as the 35 serrated plates X^2 , from the rollers X. In this case no vertical vibration would be imparted to the screens L L' .

The operation is as follows: The valve V is closed while the hopper is being filled with 40 grain. The machine is then put in operation by revolving the chain-wheel D^3 in the direction of arrow. The valve V is then opened, which allows the grain to run into the mill, which is acted upon as hereinbefore described.

45 The large grain is conducted off the screen L

into the trough Q, and thence to a receptacle placed to receive it. The remainder of the grain is caught by the screen L' , over the end of which it falls on the floor or into any suitable receptacle placed at that point to receive 50 it. The wild peas and other screenings pass through the screen L and fall onto and are conducted by the board P into the drawer P' .

Having thus described my invention, I claim—

1. In a fanning-mill, the combination and arrangement of the adjustable deflecting-board I with the air-chamber N, fans F F, upper movable riddle R, smut-board J, and hopper K, said deflecting-board I being movable to conduct the air-blast either above or below the movable upper riddle and smut-board, substantially as shown and described, and for the purpose specified.

2. In a fanning-mill, the combination and arrangement of the deflecting-board I with the air-chamber N, fans F F, upper movable riddle R, smut-board J, hopper K, having valve V, shoe S', and hangers H', said deflecting-board I being movable to conduct the 70 air-blast either above or below the upper movable riddle R and smut-board J, substantially as shown and described, and for the purpose specified.

3. In a fanning-mill, the combination, with 75 the lengthwise-reciprocating shoe S and means for operating the same, of bearings X' on the mill-frame, provided with the rollers X, the board X^3 , hinged to the shoe and provided with serrated plates X^2 , and the screen L' , 80 located in the shoe and vibrated vertically in the latter by the hinged board as the serrated plates of the latter move on the rollers, said board being adapted to swing on its hinge into the shoe to disengage the serrated plates 85 from the rollers, substantially as described.

ROBT. K. FLOETER.
